UNITED STATES PATENT OFFICE

DAVID SILBERMAN, OF NEW YORK, N. Y.

SEWING MACHINE ATTACHMENT FOR SEWING EYE TAPE

Application filed February 25, 1929, Serial No. 342,565. Renewed September 25, 1931.

My invention relates to feeding devices for sewing machines and particularly to providing sewing machines used to sew eye tape to garments with an attachment which will positively move the wire of the eyes out of the path of the needle as the latter comes down to pierce the tape and garment. In sewing eye tape to garments it often happens that the needle on its down stroke, instead of passing through the cloth, strikes the wire of which the eye is made and is broken, bent or blunted, shutting down the sewing machine until a new needle can be placed in the machine. This slows down production. Heretofore attempts have been made to provide sewing machines used for this purpose with automatic stop devices which would stop the tape with the eyes out of the path of the needle. Such devices have not been satisfactory because it is impossible to mathematically space the eyes on the stretchable tape to accurately co-operate with the stop mechanism. It is my object to provide an attachment which can be placed on a sewing machine which will always throw the wire clear of the needle path as the latter pierces the cloth, regardless of the spacing of the eyes on the tape. I accomplish this by means of a continuously vibrating arm adjacent the needle which engages the wire and throws it out of the needle path.

In the drawings Fig. 1 is a top view of my attachment;

Fig. 2 a sectional view of the structure of Fig. 1 on the line 2—2 thereof; Fig. 3 a sectional view of the structure of Fig. 1 on the line 3—3 thereof; Fig. 4 a sectional view of the structure of Fig. 1 on the line 4—4 thereof; and Fig. 5 a sectional, detail view 40 of the sliding pin pivot used in the device.

The attachment comprises a base plate 1 having a post 2 on one side thereof. A second post 3 is located on the other side of the base plate. A post 4 aligns with the post 2 and a shaft 5 is journaled in the posts 2 and 4. An arm 6 is pivoted on the shaft 5 and has a slot 7 in its free end through which passes a locking bolt 8 which is secured to the post 3.

50 A second arm 9 is pivoted on the other end

of the shaft 5 at the post 4 and is fastened by a locking bolt 10 to a post 11 on the base plate. The locking bolts, when loosened, permit a swinging motion of the arms 6 and 9 on the shaft 5.

A shaft 12 is journaled in the arms 6 and 9, as best shown in Fig. 1. A drive gear 13 and a pinion 14 are mounted on the arm 6. The gear meshes with a pinion 15 secured to the shaft 5 and the pinion 14 meshes with a gear 16 on the shaft 12, a slot 17 being cut in the base plate to give clearance for the gears. The gearing is such that the shaft 5 turns six times to one turn of the shaft 12.

The posts 4 and 11 are extended at their bases to form a face block 18. This block has a guideway secured to it consisting of a pair of plates 19—19' having a central pocket 20. A recess 21 is cut through the wall of the part 19 and partly through the wall of the part 19', as best shown in Fig. 5. The pocket 20 is cut through to the top of the parts 19—19' as best shown in Fig. 3 and a slot 23 is cut through both parts 19—19' at the rear.

The shaft 5 has an eccentric pin 5' on its end which enters into the pocket 20. The slot 23 has a pin 24 with flattened ends slidable therein as best shown in Figs. 3 and 5. A vibrator arm 25 is pivoted on the pin 24 and is provided with a rectangular hole 26. A slide block 27 with bosses 27—27' rides in the rectangular hole 26 and has a central bearing which receives the eccentric pin 5'. The revolution of the pin 5' causes the arm 25 to slide backwards and forwards as the shaft 5 revolves, the pivot pin 24 sliding in the slot 23.

The shaft 12 has an eccentric pin 12' on its end which engages a link 28. The other end of the link is pivotally secured to the arm 25. As the shaft 12 revolves the eccentric pin 12' raises and lowers the link 28 and arm 25 at the same time the shaft 5 and pin 5' are moving the arm backwards and forwards. This results in the free end of the vibrator arm having a four way movement, up and down and backwards and forwards.

The free end of the arm 25 has a serrated piece 29 secured thereto, the attaching screws 100

passing through enlarged holes therein for adjustment purposes.

In use the attachment is mounted on a sewing machine with the serrated piece 29 adjacent the needle *n*, presser foot *p* and feed dog *d*. The arms 6 and 9 are adjusted until the serrated piece 29 is at the proper height over the table to strike the wire of an eye when in lowered position. The serrated 10 piece is adjusted longitudinally on the arm 25 so that when the wire of an eye is in any serration the path of the needle on its down stroke is out of the line of the wire.

The tape and the garment are fed to the 15 presser foot by any suitable mechanism and moved under the needle by the feed dog in the usual manner. While the sewing machine is running the vibrator arm is rapidly and continuously moving back and forth and 20 more slowly up and down. On the down stroke the serrated edge hits the wire of which the eye is made and the backwards and forwards movement positively moves it out of the path of the needle as the latter makes its 25 down stroke to form a stitch. This action takes place regardless of the spacing of the eyes on the tape so that one sewing machine may be used without change for tapes having the eyes at different distances from one 30 another.

I have found in practice that the tape and wire eyes are so agitated by the rapid movement of the vibrator arm that even if the needle strikes the wire of an eye the result 35 of the collision of the two rapidly moving bodies is to cause them to glance off each other without breaking the needle.

By the use of this mechanism the speed of sewing is not reduced as there is no possibility of broken needles due to collision with the wires of the eyes.

I claim:—

1. In a feeding device for sewing machines, a base plate, a pair of parallel shafts 45 revolvably mounted thereon, a vibrator arm mounted adjacent to said shafts, means on one shaft engaging the vibrator arm for moving the same backwards and forwards, means on the other shaft engaging the vibrator arm 50 for simultaneously moving the same up and down, and a serrated plate on the free end of the arm adjacent the machine needle.

2. In a feeding device for sewing machines, a base plate, a pair of parallel shafts 55 revolvably mounted thereon, an eccentric pin on the end of each shaft, a block adjacent the shaft ends, a vibrator arm movable on said block and provided with an aperture therein, a block in said aperture engaging 60 the eccentric pin on one shaft, a link on the other eccentric pin of the other shaft connected with the vibrator arm and a serrated plate on the free end of the arm adjacent the machine needle.

3. A feeding device for sewing machines

comprising a base plate, a pair of spaced arms pivotally secured to said plate, a pair of parallel shafts revolvably mounted on said arms, a vibrator arm mounted on said base plate, a serrated plate on the free end of 70 said arm adjacent the needle and means connecting said shaft and vibrator arm whereby the latter is continuously moved forwards and backwards and up and down.

4. A feeding device for sewing machines 75 comprising a base plate, a pair of parallel shafts revolvably mounted thereon, an eccentric pin on the end of each shaft, a slotted bearing block on the base plate, a vibrator arm provided with an opening therein, a slide block in one of said openings engaging the eccentric pin on one of said shafts, a pin in the other of said openings engaging the slot in the bearing block, a link engaging the eccentric on the other shaft and the vibrator arm and a serrated plate on the free end of the vibrator arm adjacent the needle.

5. In a feeding device for sewing machines, a vibrator arm, a serrated plate on the free end thereof located adjacent the machine needle, means for continuously vibrating said arm backwards and forwards at a higher rate than the up and down vibrations, whereby the serration will engage a wire object passing under the needle and move the object out of the path of the machine needle on the down stroke of the latter.

In testimony whereof I have affixed my signature.
